COLLAR CONSTRUCTION

Herman J. Seman, Philadelphia, Pa.

Application April 20, 1938, Serial No. 203,106

4 Claims. (Cl. 2—131)

The present invention relates to a certain new and useful shirt collar construction, and it relates more particularly to a construction in collars of what may generally be referred to as a "fused" type, that is, in which the several plies of fabric are more or less permanently adhered to each other in a way which will not be affected by wetting or laundering.

One of the objects of the present invention is to produce a collar which will retain its form better and which will launder better and which will be more durable and better resist the deteriorating tendency of the laundering operations, and which will wear better, particularly at the bend or fold line.

With the above and other objects in view, which will appear more fully from the following detailed description and the accompanying drawings, the present invention consists of certain novel construction shown in the accompanying drawings and hereinbelow more fully described and defined in the appended claims.

For the purpose of illustrating the invention, there is shown in the accompanying drawings one form thereof which is at present preferred, since it has been found in practice to give satisfactory and reliable results, although it is to be understood that the various instrumentalities of which the invention consists can be variously arranged and organized and that the invention is not limited to the precise arrangement and organization of the instrumentalities as herein shown and described.

Referring to the drawings, in which like reference characters indicate like parts,

Figure 1 represents a front elevational view of a shirt including a collar embodying the present invention; all being more or less a general representation;

Figure 2 represents a plan view of the collar, with the neck-band, but with the rest of the shirt broken away. Fragments of the collar are also shown broken away, to expose to view the internal construction of the collar;

Figure 3 represents a section on line 3—3 of Figure 2;

Figure 4 represents a plan view, on a much enlarged scale (approximately 42.6 times actual size) of the outer ply of the collar;

Figure 5 represents a plan view, on a much enlarged scale (approximately 42.6 times actual size) of the intermediate ply of the collar;

Figure 6 represents a plan view, on a much enlarged scale (approximately 42.6 times actual size) of the rear ply of the collar; and

Figure 7 represents a cross-section through the three plies of the collar, on a much-enlarged scale (approximately 42.6 times actual size), taken generally on line 7—7 of Figure 2; showing the three plies of fabric before they have been pressed together.

The collar 8 of the present invention may be attached to and carried by the collar-band 9 of the shirt 10, so as to constitute a permanently attached collar in relation to the shirt, or it may be formed as a separable collar, by having a separate neck-band portion 9 associated with it independently of the shirt.

Whether of one form or another, the collar proper (8) is formed of an intermediate fusing or binding ply 11, an outer surface ply 12, and a rear ply 13.

The intermediate fusing or binding ply 11 may be of any suitable form, but includes some fusible or binding thread or members or ingredients which are capable of binding together the front and rear plies 12 and 13 in a permanent manner.

In the particular illustration shown (with particular reference to the enlarged views in Figures 5 and 7) the intermediate ply is a water-permeable ply, formed of relatively thick cellulose acetate or similar fusible or adhesive or binding threads 14 extending warpwise, closely flanked on each side by relatively thinner single-ply or single-strand cotton threads 15, and similarly thin single-ply cotton weft threads 16. The cotton warp threads 15 flanking each of the cellulose acetate threads 14 are preferably independent of and slightly separated from the pair of similar cotton warp threads which flank the next cellulose acetate threads, thereby to leave a slight gap 17 between the pairs of generally adjacent cotton warp threads. In the illustration in Figure 7 the thermoplastic binding threads 14 are shown in their initial condition before the three plies have been pressed together and before the thermoplastic thread 14 has been heated and pressed. When the three plies are pressed together to the accompaniment of heat, the thermoplastic threads 14 are squashed and generally flattened out, so that the over-all thickness of the intermediate ply 11 is less than that indicated in Figure 7;—the thickness being reduced more or less approximately to the thickness determined by the cotton threads or ingredients thereof.

The outer ply 12 is formed of similar warp and weft threads 18 and 19, respectively, each relatively thick compared to the spacing of the warp and weft threads, so that the ply will be

comparatively dense and with relatively no open spaces in any direction. The warp and weft threads 18 and 19, shown in the accompanying drawings, are preferably three-ply or three-strand mercerized cotton threads with approximately 13 to 16 twists per inch. The outer ply contains eighty threads per inch warpwise, and eighty threads per inch weftwise, and is relatively thick in contrast to ordinary shirting materials, 5 and in contrast to the ordinary outer plies commonly used in attached fused collars. The outer ply is approximately eleven to thirteen thousandths of an inch in thickness, in contrast to a thickness of about five to seven thousandths of an inch generally used for the outer ply of fused 10 collars, and in contrast to a similar thickness of five to seven thousandths of an inch used in the corresponding shirting materials.

The rear ply 13 is a relatively less dense and 20 thinner cotton ply formed of relatively thin, single-ply or single-strand warp threads 20 and relatively thin, single-ply or single-strand weft threads 21, spaced sparsely in relation to their thickness, so as to produce a fabric relatively 25 thinner and less dense and more permeable than the outer ply 12. The warp threads 20 may be relatively closely spaced, as for instance one hundred-twenty per inch, more or less, while the weft threads 21 may be spaced relatively farther 30 apart from each other, as for instance sixty-four to seventy-two threads per inch, more or less;—the weft threads 21 being relatively thin, in relation to the spacing of the weft threads to each other, so that the warp threads 20 will not 35 be bent around the weft threads 21 in sharp curves, but only in more gradual or shallow curves, as indicated more particularly in Figure 7.

The cellulose warp threads 14 of the intermediate ply 11, being thicker than the cotton threads 40 15 and 16 of the same ply, form projections 22 which serve as high contact points for the adjacent outer and rear plies 12 and 13, respectively, thereby to effect fusion or adhesion or binding at these points upon the application of heat, as in 45 the pressing or ironing operation.

It will thus be noted that the outermost ply 12 of the collar is relatively more dense than either of the two other plies, and is thicker than the rear 50 ply 13, and is also thicker than the main cotton portion of the intermediate ply 11.

The composite collar structure (upon fusion or union of the three plies) is readily permeable to water, but with the permeability being greater from the rear than from the front or outer surface. Upon laundering and pressing (ironing), good, form-retaining quality is attained. Moreover, by reason of the relatively greater density and thickness of the outer ply (in contrast to the other plies, particularly the rear ply), the repeated 55 folding or flexing of the composite structure (particularly in the dry and pressed state), will have less deteriorating effect and will produce less wear than in other fused collars. Thus, the collar construction of the present invention will greatly 60 outwear other forms of construction, and indeed, will greatly outwear or outlive the shirt to which it may be attached. Thus, it will not wear at the fold line around the folded or uppermost edge of the collar where it comes in contact with the neck.

70 While the outer ply 12 of the collar is thicker and more dense than the rear ply 13 and thicker and more dense than the shirting material (broadcloth etc.), yet it may have generally the same appearance so as to blend with the shirt and 75 to match the shirt.

The present invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having thus described the invention, what is hereby claimed as new and desired to be secured by Letters Patent, is:

1. A fused shirt collar including a relatively thick and relatively dense outer woven textile ply of from ten to fourteen thousandths of an inch in thickness, formed of twisted three-strand mercerized cotton warp threads and weft threads more or less approximately eighty threads per inch both warp-wise and weft-wise;—the thickness of said warp and weft threads being relatively great in relation to the space between threads, a 2 relatively thinner and less dense and more open-mesh rear woven textile ply formed of single-strand warp and weft threads and being relatively limper than the aforesaid outer ply, and an intermediate woven cotton ply relatively less dense 2 than the outer ply and relatively limper and carrying a thermo-plastic binding material uniting the aforementioned two other plies to form a composite collar structure in which the outer ply is substantially less limp and more form-retaining than the rear ply and less limp and more form retaining than the intermediate cotton ply, and in which composite collar structure the aforesaid outer ply dominates the two other cotton plies in any bending or flexing of the united three-ply 35 structure in such a way that said two cotton plies will yield in favor of the outer ply when the collar is bent or flexed.

2. A fused shirt collar including a relatively thick and relatively dense outer woven textile ply 40 formed of twisted three-strand mercerized cotton warp threads and weft threads;—the thickness of said warp and weft threads being relatively great in relation to the space between threads, a relatively thinner and less dense and 45 more open-mesh rear woven textile ply formed of single-strand warp and weft threads and being relatively limper than the aforesaid outer ply, and an intermediate woven cotton ply relatively less dense than the outer ply and relatively limper and 50 carrying a thermo-plastic binding material uniting the aforementioned two other plies to form a composite collar structure in which the outer ply is substantially less limp and more form retaining than the rear ply and less limp and more 55 form retaining than the intermediate cotton ply, and in which composite collar structure the aforesaid outer ply dominates the two other cotton plies in any bending or flexing of the united three 60 plies will yield in favor of the outer ply when the collar is bent or flexed.

3. A fused shirt collar including a relatively thick and relatively dense outer woven textile ply formed of twisted cotton warp threads and weft 65 threads;—the thickness of said warp and weft threads being relatively great in relation to the space between threads, a relatively thinner and less dense and more open-mesh rear woven textile 70 ply formed of warp and weft threads and being relatively limper than the aforesaid outer ply, and an intermediate woven cotton ply relatively less dense than the outer ply and relatively limper and carrying a thermo-plastic binding material 75 uniting the aforementioned two other plies to 95

form a composite collar structure in which the outer ply is substantially less limp and more form retaining than the rear ply and less limp and more form-retaining than the intermediate cotton ply, and in which composite collar structure the aforesaid outer ply dominates the two other cotton plies in any bending or flexing of the united three ply structure in such a way that said two cotton plies will yield in favor of the outer ply 10 when the collar is bent or flexed.

4. A fused shirt collar including a relatively thick and relatively dense outer woven textile ply of from ten to fourteen thousandths of an inch in thickness, formed of twisted cotton warp threads 15 and weft threads more or less approximately eighty threads per inch both warp-wise and weft-wise;—the thickness of said warp and weft threads being relatively great in relation to the space between threads, a relatively thinner and

less dense and more open-mesh rear woven textile ply formed of warp and weft threads and being relatively limper than the aforesaid outer ply, and an intermediate woven cotton ply relatively less dense than the outer ply and relatively 5 limper and carrying a thermo-plastic binding material uniting the aforementioned two other plies to form a composite collar structure in which the outer ply is substantially less limp and more form-retaining than the rear ply and less limp 10 and more retaining than the intermediate cotton ply, and in which composite collar structure the aforesaid outer ply dominates the two other cotton plies in any bending or flexing of the united three ply structure in such a way that said two 15 cotton plies will yield in favor of the outer ply when the collar is bent or flexed.
